United States Patent Office.

A. L. OTIS, OF NORMAL, ILLINOIS.

Letters Patent No. 95,256, dated September 28, 1869.

HOT-AIR FURNACE.

The Schedule referred to in these Letters Patent and making part of the same.

To all whom it may concern:

Be it known that I, A. L. OTIS, of Normal, in the county of McLean, and State of Illinois, have invented a new and useful Improvement in Heating-Furnaces; and I do hereby declare that the following is a full, clear, and exact description thereof, which will enable others skilled in the art to make and use the same, reference being had to the accompanying drawings, forming part of this specification.

This invention relates to improvements in heating-furnaces, the object of which is to provide a more economical arrangement for developing heat for heating buildings, &c.

The invention consists in certain improved arrangements of the covers of horizontal furnaces, calculated to secure the heating of the air as much as possible before passing off through the conducting-pipes;

Also, certain improvements in the construction of the walls of the furnace, calculated to give out more heat by radiation and by convection;

Also, certain improvements in the arrangement of the grates; and

Also, certain improvements in means for heating the air previous to supplying the fire, all as hereinafter more fully specified.

Figure 1 represents a transverse sectional elevation of a furnace, constructed according to my improvements;

Figure 2 represents a longitudinal sectional elevation of the same; and

Figure 3 represents a detail sectional view of the side walls.

Similar letters of reference indicate corresponding parts.

A represents a horizontal furnace, suitably enclosed with a brick jacket, B, and a sheet-metal top, C.

Instead of taking the air out from this top at one place, as in the common practice, to which the heated air will always pass in as straight lines as possible, thereby escaping a part of the surface of the heater, I propose to make the escape-passage D for the heated air the whole length of the oval top C, and to provide in the said passage a valve, E, so as to open or close the same equally throughout the whole length, whereby the heated air is caused to pass evenly over the whole surface of the top of the heater, thereby taking up more of the heat.

The side walls, which are corrugated, I provide with radiating flanges F, for the purpose of conveying the heat out into the air-space, to give it off more efficiently to the air therein by radiation and by convection.

In order to facilitate the combustion of the fuel in the furnace, as well as the radiation of heat therefrom, I provide at the back end of the furnace a V-shaped flue, H, through which the product of combustion passes in a prolonged course, calculated to increase the radiating-surface; and through this flue I pass an air-supplying perforated tube, K, leading from the back of the furnace into the interior space, terminating, preferably, near the front of the fire-chamber, at about the point a, where the air is discharged in a distributed way to the fire.

The passing of this tube through the said flue H, where it encounters the heated product of combustion, causes the air thus passing through it to be considerably heated, thereby greatly facilitating combustion.

R represents an opening formed in the rear wall of the fire-chamber, to admit the products of combustion to the flue H, in which the same first descend, then ascend to be discharged through the exit-flue N.

P is an opening made at the bottom of flue H, to permit the ready removal of the coarse products of combustion which may be deposited, or in any manner accumulate in the flue.

L M indicate, respectively, the openings to the fire-box and ash-pit.

It will, of course, be understood that the three openings, P, L, and M, above alluded to, are designed to be provided with suitable hinged or other doors.

My improvement in the arrangement of the grate consists in placing the bars in a circular line, lowest at the centre, as clearly shown at I, fig. 1, which not only increases the fire-surface, but so shapes the fire that the air passing into it from below is admitted, measurably, at the sides, as well as at the bottom.

Having thus described my invention,

I claim as new, and desire to secure by Letters Patent—

1. The arrangement of the hot-air passage D, substantially as specified.
2. The arrangement, with the side walls, of the plates F, substantially as specified.
3. The arrangement of the V-shaped flue and air supplying pipe K, substantially as specified.
4. The arrangement of the grate I, as specified.

The above specification of my invention signed by me, this 13th day of May, 1869.

A. L. OTIS
